We claim the ornamental design for a bottle, as shown and described.

DESCRIPTION

FIG. 1 is a perspective view of one embodiment of a bottle in accordance with our new design;

FIG. 2 is a right view thereof;

FIG. 3 is a left view thereof;

FIG. 4 is a front view thereof;

FIG. 5 is a back view thereof;

FIG. 6 is a top view thereof;

FIG. 7 is a bottom view thereof.

FIG. 8 is a perspective view of another embodiment of a bottle in accordance with our new design;

FIG. 9 is a right view thereof;

FIG. 10 is a left view thereof;

FIG. 11 is a front view thereof;

FIG. 12 is a back view thereof;

FIG. 13 is a top view thereof; and,

FIG. 14 is a bottom view thereof.

The uneven-length broken lines represent unclaimed boundaries of the claimed design.

The even-length broken lines showing the remainder of the bottle are for environmental purposes only and form no part of the claimed design.
